UNITED STATES PATENT OFFICE.

ISAAC ALTER, OF LAKEPORT, CALIFORNIA.

SPRING-MATTRESS.

SPECIFICATION forming part of Letters Patent No. 590,202, dated September 21, 1897.

Application filed March 1, 1897. Serial No. 625,451. (No model.)

To all whom it may concern:

Be it known that I, ISAAC ALTER, a citizen of the United States, residing at Lakeport, in the county of Lake and State of California, 5 have invented certain new and useful Improvements in Spring-Mattresses; and I do hereby declare the following to be a full, clear, and exact description of the invention, such as will enable others skilled in the art to which 10 it appertains to make and use the same.

My invention relates to improvements in bed-springs; and it consists in certain novel details of construction, combinations, and arrangements of parts hereinafter more fully 15 shown and described.

The object of the invention is to provide a simple, cheap, and durable construction adapted for application to either cots or beds.

In the accompanying drawings, Figure 1 is 20 a longitudinal sectional view of a bedstead, showing my improved springs attached thereto. Fig. 2 is a top or plan view of the same. Fig. 3 is a cross-sectional view. Fig. 4 is a plan view showing the bed-spring attached 25 to its frame. Fig. 5 is a longitudinal sectional view thereof, and Fig. 6 is a cross-sectional view.

Like numerals designate like parts throughout the several figures of the drawings.

30 Referring to the drawings, Figs. 1, 2, and 3, the numeral 1 designates a bedstead of ordinary construction provided on each side board 2 adjoining the ends thereof with cleat-blocks 3. The bed-springs comprise two end 35 slats 4 5, a center slat 6, and a series of slats or strips 7, constructed of thin sheets of spring-steel, attached to the said end bars and center bar. In practice the two end bars set down upon and are supported by the said 40 cleat-blocks. The center bar is provided at each end thereof with extensible plate-springs 8, connected with the under side thereof and fitting into sockets in the guide-blocks 9, attached to each side board of the bedstead.

45 This construction permits the longitudinal spring slats or strips to yield, and during this yielding operation the plate-springs 8 expand, and when the weight is removed from the spring-frame the said plate-springs serve to 50 assist in restoring the longitudinal slats to their normal position and thus prevent the slats from being stretched out of shape.

Normally the longitudinal slats are of greater length than the distance between the two end bars of the spring and bow or curve upward 55 at the center, so that when a weight is placed thereon the spring expands longitudinally and projects the end bars or pieces farther apart, the cleat-blocks being of sufficient length to permit this motion. Connected 60 with each of the said end bars or pieces are plate-springs 9^a, formed with a central loop 10 and two semicircular loop portions 11, said springs being secured to the end pieces by bolts 12. These springs are adapted to bear 65 against the head-piece and foot-board of the bed and give when the longitudinal spring-slats are forced down and are adapted to relieve the tension thereon and when the weight is removed from the spring-slats return the 70 latter to their normal position. Thus provision is made for this action at both the sides and ends of the bed-springs, and consequently the spring will always maintain its shape. The bow-shaped end springs also 75 serve to maintain the longitudinal spring-slats in bowed position in order to insure sufficient stiffness or rigidity to the bedstead.

In the construction shown in Figs. 4, 5, and 80 6 the bed-spring does not rest directly upon the bed, but is connected with a rectangular frame 12, said frame being adapted to rest upon the cleats ordinarily provided for supporting the slats on each side board of the bed. This spring is provided with cleats 13, in which 85 the end pieces or bars of the spring are adapted to fit and move, and with the extensible plate-springs 8, connected with the inner bar or piece of the frame and fitting in the grooved guide-blocks 9. Spiral springs 14 connect 90 the ends of the bars 12^a with the end bars or pieces of the spring and serve the same purpose as the bow-shaped springs in the other figures.

Having thus described my invention, what 95 I claim as new, and desire to secure by Letters Patent, is—

In combination with a bedstead having its side boards provided at each end with cleat-blocks or supports, and at the center with 100 grooved supports, a bed-spring comprising end bars adapted to rest upon said cleat-blocks, a center bar provided at each end with pendent extensible plate-springs adapted

to rest upon and move in said guide-blocks, a series of longitudinally-extending spring-metal slats or strips connected with said bars, and a spring connected with each end bar 5 and adapted to bear respectively against the head and foot boards of the bed and maintain the longitudinal spring-slats in proper position, substantially as described.

In testimony whereof I have signed this specification in the presence of two subscribing witnesses.

ISAAC ALTER.
